COMBINED PORTABLE SHOWER AND SUPPORT

Donald R. Quackenbush, College Place, Wash.
(2112 Marcia Drive, Bellbrook, Ohio 45305)

Filed July 11, 1969, Ser. No. 18,181

Term of patent 14 years

Int. Cl. D23—02

U.S. Cl. D23—57

FIG. 1

FIG. 2

FIG. 3

FIG. 4

FIG. 1 is an exploded front perspective view of a combined portable shower and support showing my new design;

FIG. 2 is an exploded rear perspective view thereof;

FIG. 3 is a side elevational view thereof; and

FIG. 4 is a reduced scale perspective view thereof.

The fragmentary broken line representation of a support pole and a shower curtain in FIG. 4 is for purposes of illustration only.

I claim:

The ornamental design for a combined portable shower and support, as shown and described.
